US0D1059268S

(12) **United States Design Patent** (10) **Patent No.:** **US D1,059,268 S**
(45) **Date of Patent:** **** Jan. 28, 2025**

(54) **BATTERY PACK**

(71) Applicants: **Jinko Energy Storage Technology Co., Ltd.**, Haining (CN); **Shanghai Jinko Green Energy Enterprise Management Co., Ltd.**, Shanghai (CN)

(72) Inventor: **Wei Li**, Haining (CN)

(73) Assignees: **JINKO ENERGY STORAGE TECHNOLOGY CO., LTD.**, Haining (CN); **SHANGHAI JINKO GREEN ENERGY ENTERPRISE MANAGEMENT CO., LTD.**, Shanghai (CN)

(**) Term: **15 Years**

(21) Appl. No.: **29/904,047**

(22) Filed: **Sep. 29, 2023**

(30) **Foreign Application Priority Data**

Mar. 31, 2023 (CN) 202330169329.0

(57) **CLAIM**

The ornamental design for a battery pack, as shown and described.

DESCRIPTION

FIG. 1 is a perspective view of a battery pack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 1.

1 Claim, 10 Drawing Sheets
